UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

WATER BOWL.

Application filed December 4, 1925. Serial No. 73,162.

This invention relates to water bowls, particularly to the animal-operated type adapted to be used in dairy barns and the like. There are two general types of water bowls on the market known as detachable and non-detachable. The former are cleaned and sterilized by removing and washing in boiling water. The latter are cleaned by scraping out such feed and débris as collect there from time to time, but no sterilization of this bowl can readily take place. The lower cost however creates a demand for the non-detachable bowl.

Since both types of bowl must be kept in stock, it is highly desirable that a single bowl be made to serve both purposes, thereby greatly reducing the cost of handling.

Many more or less successful attempts have been made to develop a satisfactory bowl which is readily removable for the purpose of cleaning. The weight of the bowl however even in the smaller types make its use objectionable in many ways. For example, these bowls weigh from eight to eleven pounds or more and consequently can be cleaned only in a large tank which must either be wheeled to a point near the stalls where the water bowls are used or the heavy bowls carried some distance to the tank. The former is further complicated by the fact that this tank must be heated to sterilize these bowls.

An object of the present invention is to provide a suitable water bowl of a type required for this service in which the bowl can readily be removed, washed and replaced without the expenditure of much time or effort and without necessitating the installation of costly equipment to do it.

Another object is the provision of a light bowl made of sheet metal which is more sanitary than cast bowls which are more or less filled with sand holes in which food lodges and deteriorates.

Another object is to reduce the stocks of bowls needed to be carried by dealers in order to supply both removable and non-removable bowls.

These and other objects which will hereinafter appear are accomplished by this invention, which is fully described in the following specification and shown in the accompanying drawings, in which:

Figure 1 is a side elevation of the device showing the bowl in section; and

Fig. 2 is a top plan view of the same.

The embodiment illustrated comprises a bowl 10 preferably of semi-spherical form having a lug 11 at one side through which pass bolts 12 for securing it to ears 13 on a hollow casing 14. The latter is preferably threaded top and bottom to receive water pipes 15 and 16.

This casting contains a valve mechanism of the type shown in Ferris Patent No. 1,479,499, granted January 1, 1924, and has a valve stem 17 projecting through the front member 18. A valve operating lever 19 is hingedly mounted on a pin 20 passing through the upper portion of the front member 18. This operating lever normally rests against the outer end of the valve stem 17, the lower end of the lever extending into the bowl 10.

It will be understood from the foregoing that, as the animal presses its muzzle into the bowl to obtain a drink, it will depress the lower end of the lever 19 thereby pressing inwardly the valve stem 17 and admitting water to the bowl from the pipe 15 which is connected to any suitable source of water supply. The water bowl as previously described is complete in itself and may be carried in stock by dealers and sold in this form to those users who do not wish to go to the extra trouble necessary to keep the bowls clean and sanitary. Where, however, the user wishes to have a bowl which is readily rendered sanitary, he may be supplied with a lining 21 which is preferably spun or pressed from sheet metal such as brass or copper and is so formed that the lining will fit snugly into the bowl 10. The outer edge of the lining is rolled outwardly at 22 and is adapted to fit into the ledge 23 of the bowl. A lip 24 on the casting 14 overlies the inner edge of the lining 21 so as to assist in retaining the latter in place in the bowl. A clip 25 of spring sheet metal or the like is secured to the lining 21 as by means of rivets 26 and this clip is so placed as to be nearly opposite the lip 24. This clip snaps over the outer edge of the bowl and, together with the lip 24 retains the lining in the bowl so that it is not readily dislodged by an animal rubbing his muzzle about the bowl.

Thus it will be seen that a very substantial water bowl is provided which, at the same time, provides a removable bowl lining which is light but strong and which can be

removed from the bowl proper and nested one within the other and thus a number of them may be placed in a relatively small container where they may be readily sterilized by boiling. Owing to the lightness of the lining even a child can carry a number of them some distance so that the cumbersome sterilizing tanks frequently used are no longer required.

10 While I have shown and described but two embodiments of this invention, it is to be understood that it is capable of many modifications. Changes therefore in the construction and arrangement may be made 15 which do not depart from the spirit and scope of the invention as disclosed in the appended claims.

I claim:

1. In combination, a supporting structure 20 of bowl-like form, a support therefor, means for supplying water to said supporting structure including a valve, an animal-operated lever within the supporting structure for opening said valve, an imperforate metal 25 removable lining for said supporting struc-

ture, and coacting means on said supporting structure and lining for releasably retaining said lining therein.

2. In a water bowl, a hollow member 30 adapted to be secured to a support, a supporting structure of bowl-like form secured to said member, a water valve in said member, a valve-operating member extending into the supporting structure, a removable 35 lining for said supporting structure, said lining extending under the housing for said valve, and coacting means on said lining and supporting structure for retaining the lining in the supporting structure.

3. In a water bowl, a hollow member 40 adapted to be secured to a support, a supporting structure of bowl-like form secured to said member, a water valve in said member, a valve-operating member extending 45 into the supporting structure, a removable lining for said supporting structure, said lining extending under the housing for said valve, and a spring clip on said lining for retaining it in the supporting structure.

HENRY L. FERRIS.
